MECHANISM FOR DELIVERING MATERIAL

Edward B. Story, Dormont, and William T. Case,
Beaver, Pa., assignors to A. M. Byers Company,
Pittsburgh, Pa., a corporation of Pennsylvania

Application August 10, 1932, Serial No. 628,125

18 Claims. (Cl. 266—38)

- This invention relates broadly to mechanism for delivering material, and more particularly to mechanism for enabling controlled delivery of material in a more or less continuous stream.
- 5 The invention relates still more particularly to mechanism for delivering material from a receptacle in a stream of substantially constant cross-section so that the rate of delivery is substantially constant.
- 10 In certain of its more specific aspects the invention relates to pouring material, such as liquid or semi-liquid material, from a receptacle, as by tilting the receptacle, and controlling the rate of pour. The rate of pour is preferably controlled by the weight of the material being poured.

It is often desirable to deliver material in a more or less continuous stream at a controlled rate. For certain purposes it is particularly desirable to deliver material in a continuous stream 20 of substantially constant cross-section so that the rate of delivery of the material remains substantially constant. For example, in the manufacture of wrought iron by the Aston process in which, in one method of procedure, a stream of molten ferrous material is introduced into a bath of molten slag, it is desirable to introduce the ferrous material at a constant rate. This has been found difficult due to the great weight and bulk of the materials and the heavy and cumbersome machinery necessary. In the manufacture 30 of wrought iron by the Aston process it has heretofore been the practice to manually control the rate of pour, as, for example, by controlling by a hand rheostat a motor connected with a tilting receptacle, so as to pour the ferrous material from such receptacle in as nearly uniform a stream as possible by hand control.

We have devised mechanism for delivering material which is particularly well adapted for use 40 in introducing molten ferrous material into a slag bath in the manufacture of wrought iron by the Aston process, but which is also suitable for many other purposes. We provide for automatic control of the rate of delivery of the material so 45 that such rate remains substantially constant without the need of manual control.

Other details, objects and advantages of the invention will become apparent as the following description of a present preferred embodiment 50 thereof proceeds.

In the accompanying drawings we have shown a present preferred embodiment of the invention, in which

Figure 1 is a diagrammatic elevational view 55 of mechanism for delivering material;

Figure 2 is an enlarged detail view of a portion of the mechanism shown in Figure 1;

Figure 3 is a plan view of the mechanism shown in Figure 2;

Figure 4 is an end view of the mechanism shown 5 in Figures 2 and 3; and

Figure 5 is a diagrammatic view illustrating the operation of a portion of the mechanism.

Referring more particularly to the drawings, there is provided a base 2 upon which is mounted 10 for longitudinal reciprocatory motion a platform 3 which in turn carries a horizontally rotatable ladle support 4. Carried on the ladle support 4 are trunnion supports 5 which carry a ladle 6 for tilting movement about trunnions 7. The tilting 15 of the ladle is effected by a motor 8 operating through reduction gearing 9. The ladle carries a worm wheel 51 with which meshes a worm 52 carried on a shaft 53 which is connected through a coupling 54 with a shaft 55 leading from the reduction gearing 9. The reduction gearing 9 is 20 connected with the motor 8 by shafts 56 and 57 joined by a coupling 58.

The mechanism just described may be of the type described and claimed in the copending application of Fredrik H. Wille, Serial No. 423,979, filed January 28, 1930. The reciprocation of the platform 3 and the rotation of the ladle support 4 are effected by mechanism not shown in the drawings of this application but fully disclosed 30 in said Wille application. Such mechanism forms no part of the present invention, which is directed more particularly to the rate of delivery of material from the ladle. Therefore, for present purposes the ladle support may be regarded 35 as stationary.

There is provided a standard 10 carrying an upright 11 on which is fulcrumed at 12 (Figure 4) a balance beam 13. The longer arm of the beam is toward the right, viewing Figure 2, and such 40 arm carries a poise 14 adapted to travel along the beam, as will presently be described. The shorter arm of the beam is toward the left, viewing Figure 2, and a connection, diagrammatically indicated at 15 (Figure 1), extends from such 45 arm in such manner that the weight of the base 2 and everything carried by it tends to pull down the shorter arm of the beam 13. Such connection may be formed in accordance with usual practice in the scale art. Weights 16 are provided at the end of the right-hand arm of the beam 13 and may be used to counterbalance the weight of the base 2 and the mechanism carried thereby when the ladle 6 is empty so that the beam may be balanced with the poise 14 at the 50 55

zero mark, which is near the right hand end of the beam 13, viewing Figures 1 and 2. A balancing weight 17 is also provided.

Journalled in the beam 13 is a screw 18 with which a detent 19 carried by the poise 14 is adapted to cooperate so that upon rotation of the screw the poise will be moved longitudinally of the beam. The screw shaft carries a bevel gear 20 which meshes with a bevel gear 21 carried by a cross shaft 22 mounted in the upright 11. The shaft 22 carries gears 23, one at either end, which respectively mesh with gears 24 carried by oppositely disposed shafts 25. One of the shafts 25 carries a hand wheel 26 and the other carries a sprocket 27. The sprocket 27 is mounted loosely on its shaft and may rotate without rotating the shaft. Splined to such shaft is a clutch member 28 which is operable axially of the shaft by a solenoid 29 and a coil spring 30. The coil spring 30 normally urges the clutch member 28 toward the right, viewing Figure 4, and energization of the solenoid draws the clutch member toward the left. In Figure 4 the clutch member is shown in disengaged position, that is, in its left-hand position, where it is held by energization of the solenoid against compression of the spring 30. When the solenoid is deenergized the spring pushes the clutch member toward the right where it engages the hub 31 of the sprocket 27, causing the shaft to which the clutch member is splined to rotate with the sprocket.

There is provided a motor 32 which drives, through suitable reduction gearing, a gear 33. Meshing with the gear 33 is another gear 34 keyed to a shaft 35, which shaft also carries a sprocket 36 connected with the sprocket 27 by a sprocket chain 37. The motor 32 may be a variable speed motor, or provision may be made for changing the gears 33 and 34 so that different speeds of rotation may be imparted to the sprocket 36, and consequently to the sprocket chain 37, and the mechanism driven thereby.

Referring now more particularly to Figure 5, the armature of the motor 8 for tilting the ladle 6 is designated diagrammatically at 38, the series field at 39, the shunt field at 40 and a resistance in series with the shunt field at 41. Current is supplied to the motor through power lines 42. Leads 43 lead to a relay 44 so that when the circuit through the leads 43 is closed by the relay a circuit of low resistance in parallel with the relatively high resistance 41 will be formed, such circuit having the effect of cutting out the resistance 41 as the current will flow through the leads 43 instead. The relay 44 is connected by leads 45 with a light-sensitive device 46 which may be an ordinary photoelectric cell, or what is commonly known as an "electric eye". A source of light 47 is provided for cooperation with the light-sensitive device and the end of the beam 13 carries a diaphragm 48 which, in the lower position of the beam, interrupts the light rays between the source of light and the light-sensitive device.

When the light rays are thus interrupted the light-sensitive device is effective through the relay 44 for closing the circuit through the leads 43 which cuts out the resistance 41 and causes the motor 8 to operate at a slower speed. When the beam is in its upper position the circuit through the leads 43 is broken so that the resistance 41 becomes effective, causing the motor 8 to operate at a faster speed.

75 A typical operation of the mechanism will now

be described. With the ladle 6 empty the poise 14 is placed at the zero mark on the scale-beam and the beam is balanced by the addition of a suitable number of weights 16 and by manipulation of the balancing weight 17. A desired amount of material is then introduced into the ladle 6 and the beam is balanced after the ladle has thus been filled, such balancing being effected by moving the poise 14 along the beam until the point of balance is reached. By suitable graduations on the beam the weight of material in the ladle can thus be ascertained.

With the clutch 28 open the motor 32 is then started, such motor being effective through the gears 33 and 34 and the sprocket 36 and sprocket chain 37 for rotating the sprocket 27. The sprocket 27 being loosely carried on its shaft, such shaft does not rotate when the clutch is open. The speed of the motor 32 or the size and relation of the gears 34 and 35 are adjusted to drive the sprocket 27 at a desired speed which will determine, as will presently be described, the rate of unloading of the beam 13 when the clutch 28 is engaged, and consequently also, through the other mechanism provided, the rate of pouring of material from the ladle 6.

The motor 8 is then started which will commence the tilting operation of the ladle. Unless the ladle has been filled up to its lip, some degree of tilting will be required before the material begins to issue from the lip of the ladle. The operator watches the ladle and as soon as material begins to issue from its lip he deenergizes the solenoid 29, which permits the spring 30 to move the clutch member 28 into engagement with the hub 31 of the sprocket 27. This causes rotation of the shaft upon which the sprocket 27 is mounted, which, in turn, through the corresponding gears 24 and 23, the shaft 22 and the bevel gears 21 and 20, causes rotation of the screw 18 carried by the beam 13. Rotation of the screw 18 causes movement of the poise 14 along the beam toward the left, viewing Figure 2. This causes progressive unloading of the beam at the rate at which it is desired to pour material from the ladle 6.

The motor 8 and its cooperative mechanism are so constructed and arranged that the speed of tilting of the ladle 6 when the resistance 41 is effective, and consequently at the higher speed of the motor, is slightly greater than the maximum tilting speed required at any time during the pour to deliver material from the ladle at the desired rate, that is to say, at the rate corresponding to the rate of unloading of the beam 13 by movement of the poise 14 therealong, as above described. Likewise, at the lower speed of the motor, that is, when the resistance 41 is not effective, the speed of tilting of the ladle 6 is slightly less than the minimum tilting speed required at any time during the pour to deliver material from the ladle at the desired rate.

As soon as the material begins to issue from the lip of the ladle 6 and the clutch member 28 has been engaged the ladle will be delivering material at a rate roughly approximating the desired rate of delivery and the poise 14 will be moving along the beam 13 at precisely the desired rate of delivery. If the rate of pour exceeds the desired rate, that is to say, if the rate of unloading of the ladle exceeds the rate of unloading of the beam, the right-hand arm of the beam, viewing Figure 2, will assume its lower position, which, as above explained, is effective for interposing the diaphragm 48 in the path of light passing from the light rays 47 to the light-sensitive device 46, 75

which, in turn, is effective, through the relay 44, for closing the circuit through the leads 43, thus effectively cutting out the resistance 41 and reducing the speed of the tilting motor 8. This 5 reduces the rate of issuance of material from the lip of the ladle 6 to a point slightly below the desired pouring rate so that the rate of unloading of the ladle will thereafter be somewhat less than the rate of unloading of the beam. This 10 condition will continue until the weight of the metal in the ladle overbalances the beam, when the right-hand arm of the beam, viewing Figure 2, will assume its upper position, permitting light from the light source 47 to impinge upon the 15 light-sensitive device 46, which is effective, through the relay 44, for opening the circuit through the leads 43, thus effectively throwing in the resistance 41 and speeding up the tilting motor 8. Thus upon each movement of the beam 20 the rate of pour is slightly increased or decreased so that the average rate very closely approaches the desired rate of pour.

Thus the contents of the ladle can be automatically delivered at substantially a predetermined uniform rate, eliminating manual control. 25 This has the advantages not only of doing away with the human element but also of reducing labor costs. As above mentioned, the mechanism is of particular advantage and utility for use 30 in introducing molten ferrous material into a bath of molten slag in the manufacture of wrought iron by the Aston process in which the rate of introduction of the ferrous material should be as nearly uniform as possible.

15 The mechanism is equally well adapted for delivery of material at a desired predetermined non-uniform rate. To this end the speed of the motor 32 can be altered during the pour, either manually or automatically.

20 Instead of manually controlling the solenoid 29 to throw in the clutch 28, operation of such solenoid may be controlled automatically. This would eliminate the need of any manual operation during the pour.

25 The hand wheel 26 may be used for moving the poise 14 along the beam 13 when the clutch 28 is disengaged. Rotation of the hand wheel causes rotation of its shaft and of the corresponding gear 24 which, through the gear 23 meshing therewith, rotates the shaft 22, the bevel gears 21 and 20, and consequently the screw 18 which propels the poise along the beam. When the ladle is being filled with material prior to the pour, the hand wheel 26 may be used to 30 keep the beam in balance and may thus serve to assist in determining the amount of material supplied to the ladle. If the beam is kept in balance, or approximately so, during supply of material to the ladle, this has the advantage that the 35 operator will have advance warning when the amount of material supplied to the ladle nears the desired amount. Such advance warning is of particular advantage when the mechanism is used for the manufacture of wrought iron by the Aston process, as the molten ferrous material may be supplied to the ladle by a tilting ladle carried by an overhead crane, control of which is relatively difficult.

The details of construction of the motors and 40 their control mechanism, the light-sensitive device 46 and the relay 44 have not been shown or described because such devices may be, and preferably are, of well known standard construction such as may be purchased in the open market.

Instead of utilizing the light-sensitive device 46 for controlling the tilting motor, suitable electric contacts or other devices may be used which may be directly engaged by the beam 18 upon movement to its upper and lower positions.

5 While we have shown and described certain present preferred embodiments of the invention, it is to be distinctly understood that the same is not limited thereto, but may be otherwise variously embodied within the scope of the following claims.

We claim:

1. Mechanism for delivering material, comprising delivery means, movable control means, means for exerting on the control means a variable force the rate of change in the effectiveness of which on the control means bears a predetermined relationship to the desired rate of delivery, connections through which a second variable force opposed to the first is exerted on the control 15 means, the rate of change in the effectiveness of said second force on the control means bearing a predetermined relationship to the actual rate of delivery, and means operable upon movement of the control means in response to said forces when the actual rate of delivery is less than that desired for increasing such actual rate of delivery of material from the delivery means.

2. Mechanism for delivering material, comprising delivery means, control means movable in response to the resultant of two opposed variable forces the rates of change in the effectiveness of which on the control means bear predetermined relationships respectively to the desired and actual rates of delivery, and means operable upon movement of the control means in response to said resultant when the actual rate of delivery is less than that desired for increasing such actual rate of delivery of material from the delivery means.

3. Mechanism for delivering material, comprising a delivery receptacle, movable control means, a source of energy, means operable by said source of energy to exert on the control means a variable force the rate of change in the effectiveness of which on the control means is proportional to the desired rate of delivery from said receptacle, connections sensitive to the change in the amount of material in said receptacle on delivery of material therefrom to exert on the control means a second variable force opposed to the first the rate of change in the effectiveness of which on the control means is proportional to the actual rate of delivery from said receptacle, and means operable upon movement of the control means in response to said forces when the actual rate of delivery is less than that desired for increasing such actual rate of delivery of material from said receptacle and operable upon movement of the control means in response to said forces when the actual rate of delivery is greater than that desired for decreasing such actual rate of delivery of material from said receptacle.

4. Mechanism for delivering material, comprising a delivery receptacle, movable control means,

a source of energy, means operable by said source of energy to exert on the control means a variable force the rate of change in the effectiveness of which on the control means bears a predetermined relationship to the desired rate of delivery from said receptacle, connections sensitive to the weight of material delivered from said receptacle to exert on the control means a second variable force opposed to the first the rate of change in the effectiveness of which on the control means bears a predetermined relationship to the actual rate of delivery from said receptacle, and means operable upon movement of the control means in response to said forces when the actual rate of delivery is less than that desired for increasing such actual rate of delivery of material from said receptacle.

5. Mechanism for delivering material, comprising a tiltable delivery receptacle, movable control means, a source of energy, means operable by said source of energy to exert on the control means a variable force the rate of change in the effectiveness of which on the control means bears a predetermined relationship to the desired rate of delivery from said receptacle, connections sensitive to delivery of material from said receptacle to exert on the control means a second variable force opposed to the first the rate of change in the effectiveness of which on the control means bears a predetermined relationship to the actual rate of delivery from said receptacle, and means operable upon movement of the control means in response to said forces when the actual rate of delivery is less than that desired for increasing the rate of tilting of the receptacle and operable upon movement of the control means in response to said forces when the actual rate of delivery is greater than that desired for decreasing the rate of tilting of the receptacle.

6. Mechanism for delivering material, comprising a delivery receptacle, control means movable by the resultant of a predeterminedly effective independently applied variable force and an independently variable force opposed to said first mentioned force and bearing a predetermined relationship to the rate of delivery of material from said receptacle, and means operable upon movement of the control means in response to said resultant when the actual rate of delivery is less than that desired for increasing such actual rate of delivery of material from said receptacle and operable upon movement of the control means in response to said resultant when the actual rate of delivery is greater than that desired for decreasing such actual rate of delivery of material from said receptacle.

7. Mechanism for delivering material, comprising a delivery receptacle, connections operable in predetermined relationship to the rate of delivery of material from said receptacle, control means movable by the resultant of a predeterminedly effective independently applied variable force and an independently variable force opposed to said first mentioned force and controlled by said connections, and means operable upon movement of the control means in response to said resultant when the actual rate of delivery is less than that desired for increasing such actual rate of delivery of material from said receptacle and operable upon movement of the control means in response to said resultant when the actual rate of delivery

is greater than that desired for decreasing such actual rate of delivery of material from said receptacle.

8. Mechanism for delivering material, comprising a delivery receptacle, movable control means, a source of energy, means operable by said source of energy to exert on the control means a variable force the rate of change in the effectiveness of which on the control means bears a predetermined relationship to the desired rate of delivery from said receptacle, connections exerting on the control means a second variable force opposed to the first the rate of change in the effectiveness of which on the control means bears a predetermined relationship to the actual rate of delivery from said receptacle, and means operable upon movement of the control means in response to said forces when the actual rate of delivery is less than that desired for increasing such actual rate of delivery of material from said receptacle and operable upon movement of the control means in response to said resultant when the actual rate of delivery is greater than that desired for decreasing such actual rate of delivery of material from said receptacle.

9. Mechanism for delivering material, comprising a delivery receptacle, control means movable by the resultant of a predeterminedly effective independently applied variable force and an independently variable force opposed to said first mentioned force and controlled by the change in the amount of material in said receptacle on delivery of material therefrom, and means operable upon movement of the control means in response to said resultant when the actual rate of delivery is less than that desired for increasing such actual rate of delivery of material from said receptacle and operable upon movement of the control means in response to said resultant when the actual rate of delivery is greater than that desired for decreasing such actual rate of delivery of material from said receptacle.

10. Mechanism for delivering material, comprising a delivery receptacle, control means including a tiltable beam movable by the resultant of a predeterminedly effective independently applied variable force and an independently variable force opposed to said first mentioned force and controlled by delivery of material from said receptacle, and means operable upon movement of the control means in response to said resultant when the actual rate of delivery is less than that desired for increasing such actual rate of delivery of material from said receptacle and operable upon movement of the control means in response to said resultant when the actual rate of delivery is greater than that desired for decreasing such actual rate of delivery of material from said receptacle.

11. Mechanism for delivering material, comprising a delivery receptacle, control means movable by the resultant of a predeterminedly effective independently applied variable force and an independently variable force opposed to said first mentioned force and controlled by delivery of material from said receptacle, and means including light-sensitive means operable upon movement of the control means in response to said resultant when the actual rate of delivery is less than that desired for increasing such actual rate of delivery of material from said receptacle and operable upon movement of the control means in response to said resultant when the actual rate of delivery is greater than that desired for decreasing such

- actual rate of delivery of material from said receptacle.
12. Mechanism for delivering material, comprising a delivery receptacle, control means including a tilttable beam movable by the resultant of a predeterminedly effective independently applied variable force and an independently variable force opposed to said first mentioned force and controlled by delivery of material from said receptacle, and means operable upon tilting of said beam in response to said resultant when the actual rate of delivery is less than that desired for increasing such actual rate of delivery of material from said receptacle and operable upon tilting of said beam in response to said resultant when the actual rate of delivery is greater than that desired for decreasing such actual rate of delivery of material from said receptacle.
13. Mechanism for delivering material, comprising a delivery receptacle, control means including a tilttable beam movable by the resultant of a predeterminedly effective independently applied variable force and an independently variable force opposed to said first mentioned force and controlled by delivery of material from said receptacle, and light-sensitive means operable upon tilting of said beam in response to said resultant when the actual rate of delivery is less than that desired for increasing such actual rate of delivery of material from said receptacle and operable upon tilting of said beam in response to said resultant when the actual rate of delivery is greater than that desired for decreasing such actual rate of delivery of material from said receptacle.
14. Mechanism for delivering material, comprising a delivery receptacle, control means including a tilttable beam, a poise predeterminedly movable along said beam, said beam being tilttable by the resultant of the variable force applied by movement of said poise therealong and an independently variable force opposed to said first mentioned force and controlled by delivery of material from said receptacle, and means operable upon tilting of said beam in response to said resultant when the actual rate of delivery is less than that desired for increasing such actual rate of delivery of material from said receptacle and operable upon tilting of said beam in response to said resultant when the actual rate of delivery is greater than that desired for decreasing such actual rate of delivery of material from said receptacle.
15. Mechanism for delivering material, comprising a tilttable delivery receptacle, control means movable by the resultant of a predeterminedly effective independently applied variable force and an independently variable force opposed to said first mentioned force and controlled by delivery of material from said receptacle, and means operable upon movement of the control means in response to said resultant when the actual rate of delivery is less than that desired for increasing the rate of tilting of said receptacle and operable upon movement of the control means in response to said resultant when the actual rate of delivery is greater than that desired for decreasing the rate of tilting of said receptacle.
16. Mechanism for delivering material, comprising a delivery receptacle, control means including a fulcrumed member, means for applying to said fulcrumed member a predeterminedly effective variable force, means for applying to said fulcrumed member an independently variable force opposed to said first mentioned force and controlled by delivery of material from said receptacle, and means operable upon movement of said fulcrumed member under the action of said forces when the actual rate of delivery is less than that desired for increasing such actual rate of delivery of material from said receptacle and operable upon movement of said fulcrumed member under the action of said forces when the actual rate of delivery is greater than that desired for decreasing such actual rate of delivery of material from said receptacle.
17. Mechanism for delivering material, comprising a delivery receptacle, means controlling delivery of material from said receptacle, means movable by the resultant of a predeterminedly effective independently applied variable force and an independently variable force opposed to said first mentioned force and controlled by delivery of material from said receptacle, and means operable upon movement of said last mentioned means in response to said resultant when the actual rate of delivery is less than that desired for actuating said first mentioned means to increase such actual rate of delivery of material from said receptacle and operable upon movement of said last mentioned means in response to said resultant when the actual rate of delivery is greater than that desired for actuating said first mentioned means to decrease such actual rate of delivery of material from said receptacle.
18. Mechanism for delivering material, comprising a delivery receptacle, electrically actuated means controlling delivery of material from said receptacle, and means movable by the resultant of a predeterminedly effective independently applied variable force and an independently variable force opposed to said first mentioned force and controlled by delivery of material from said receptacle, said last mentioned means being operable in response to said resultant when the actual rate of delivery is less than that desired for controlling said electrically actuated means to increase such actual rate of delivery of material from said receptacle and being operable in response to said resultant when the actual rate of delivery is greater than that desired for controlling said electrically actuated means to decrease such actual rate of delivery of material from said receptacle.
